COMBINATION NIGHT-LIGHT AND TOILET ARTICLE HOLDER AND STERILIZER
Douglas G. Ellis, 7246 N. Newell Ave.,
Portland, Oreg. 97203
Filed Dec. 21, 1964, Ser. No. 419,813
1 Claim. (Cl. 21—102)

This invention relates to a new and novel combination night-light and toilet article holder and sterilizer.

A primary objective of the present invention is to provide a novel combination of structure which incorporates means for conveniently holding one or more toothbrushes as well as other toilet articles and means for sterilizing the toilet articles during the time that they are not in use.

It is a more particular object of the present invention to provide a holder for toilet articles in which is incorporated a fluorescent and sterilizing light bulb, and including compartments for holding toothbrushes under the light bulb so that ultra violet sterilizing can be achieved.

Another object is to provide a holder for toothbrushes in which is incorporated sterilizing means and including a novel arrangement of toothbrush receiving pockets wherein the said toothbrushes are readily positioned for sterilization and at the same time are conveniently placed in and removed from the holder.

Still another object is to provide a toothbrush holder having sterilizing light means therein which in addition to serving a sterilizing function also serves to provide a night-light for the room in which the holder is contained.

Additional objects will become apparent from the following specification and claim, considered together with the accompanying drawings, wherein the numerals of reference indicate like parts.

In the drawings:

FIGURE 1 is a perspective view of the present combination night-light and toilet article holder and sterilizer;

FIGURE 2 is a vertical sectional view taken on the line 2—2 of FIGURE 1; and

FIGURE 3 is a horizontal, sectional view taken on the line 3—3 of FIGURE 1.

Referring now in particular to the drawings, which show a preferred embodiment of the invention, the holder has a pair of side walls or plates 10 which may be of the shape shown comprising a widened rectangular lower portion and a narrow or tapered upper portion rounded at the upper end 12. The holder has a back wall 14 and a bottom wall 16. In a preferred construction, the back wall 14 is curved forwardly at its upper end and projects forwardly over the curved upper ends 12 of the side plates 10 to form a top wall 18. As will be seen hereinafter, the portion 18 serves as a shield or diffusing element for light means in the holder.

The holder has one or more compartments 20 leading from front to rear at the lower end thereof. These compartments are formed by upright wall portions 22 integral with the bottom wall 16 and interconnected at their top by a horizontal shelf or plate 24. As best seen in FIGURE 2, the wall portions 22 project fully from front to rear of the holder, and the shelf 24 projects from the front end but terminates short of the rear wall 14, whereby to form rear openings 26 between the interior of the holder and the compartments 20. Compartments 20 are of selected dimension to freely receive the bristle end of toothbrushes 28 and are of sufficient length such that the center of gravity of the toothbrushes will be disposed inwardly from the front edge. The compartments, however, are preferably of a length which will permit the handle end of the toothbrush to project a certain extent for easy grasping and removal of the toothbrush therefrom.
